J. MESSMER

QUICK OPENING VALVE

Filed August 1, 1921

Inventor:
Joseph Messmer.
By Elliott & Munro
Attorneys

UNITED STATES PATENT OFFICE.

JOSEPH MESSMER, OF ST. LOUIS, MISSOURI, ASSIGNOR TO FRED MESSMER MANUFACTURING COMPANY, OF ST. LOUIS, MISSOURI.

QUICK-OPENING VALVE.

Application filed August 1, 1921. Serial No. 488,762.

This invention relates to valves or water cocks, and the general object of the invention is to produce a simple quick-opening and closing valve which can be moved from its closed position to its full-open position by a relatively short movement of the hand-operated part that controls the valve. One of the objects of the invention is to provide a construction which will avoid the use of threads for enabling the valve to be screwed upon its seat. While my valve may be used for various purposes it is especially useful as applied to washing machines to enable the contents of the tub to be drained off into a bucket. Where a drain valve is opened or closed by a threaded connection the opening and closing movement of the valve is so slow that the bucket receiving the water may become filled and overflow before the valve can be completely closed.

With a valve constructed according to my invention the valve lever can be held in one's hand and with a slight movement of this lever the valve can be opened full or held in any partially open position desired. One of the objects of the invention is to provide means for packing a valve of this type which will prevent leakage.

Further objects of the invention will appear hereinafter.

The invention consists in the novel features, and in the general combination of parts to be particularly described herein-after, all of which contribute to produce a simple and efficient quick-opening valve. A preferred embodiment of my invention will be particularly described in the following specification, while the broad scope of my invention will be pointed out in the appended claims.

In the drawing:

Figure 1 is a side elevation of a valve embodying my invention, certain parts being broken away to illustrate details of the valve; this view shows the valve in its full-open position;

Figure 2 is a vertical section through the valve shown in Figure 1 but illustrating the valve in its closed position;

Figure 3 is a plan of the valve partially broken away; and

Figure 4 is a vertical section through the valve taken on the line 4—4 of Figure 1

but merely showing the bracket and the round member or ball carried thereby. 55

Referring more particularly to the parts, the casing 1 of this valve includes a body 2 which may be provided with a flange 3 which facilitates the same being attached to the under side of a tub or other vessel 4 which the valve is to drain. The valve may, of course, be of any type, but the valve illustrated is of elbow-form provided with an opening 5 through a seat 6, which is adapted to be closed at will by a valve including a valve disk 7 carrying a gasket or washer 8 adapted to come upon the seat when the valve is closed. The valve includes a stem 9 to which the disk 7 is attached and this stem is guided in the casing, 70 that is to say, it is guided by and passes through a bonnet 10 which is detachably secured to the body 2 by screw-threads 11.

According to my invention I provide a cam which is provided with a manually 75 operated member such as a lever 12. By rotating the lever the cam forces the valve upon its seat. The valve and cam are so related that they co-operate so as to enable the valve and cam to maintain themselves 80 in any position in which they are left. I prefer to provide a spring associated with the valve in such a way that it will open the valve when the cam permits. For this purpose I prefer to provide a bracket 13 which is detachably mounted in a bore 14 in the outer side of the bonnet. Any suitable means may be provided for securing this bracket. For example, I may secure it in position by two taper pins 15 which are driven into holes drilled partly in the wall 85 of the bore 14 and partially through a cylindrical neck 16 on the bracket, which fits into the bore 14. The outer end of the stem 9 is provided with a collar 17 which may be 90 secured by means of a pin 18, and a small coil spring 19 is provided around the valve stem which thrusts at its outer end against the head 17 and which exerts its force at its 95 inner end to hold a packing or packing washer 20 firmly against the bottom of the bore 14 and around the opening in the bonnet through which the stem 9 passes. The spring does not thrust directly against the 100 packing 20, which by the way, should be a soft vegetable packing, but it thrusts against

105

a rigid washer 21. This washer, if desired, may fit neatly in a central bore 22 formed through the bracket 13. This bore 22 also operates to receive a round anti-friction member or ball 23 which is engaged by the edge of a cam 24. The bracket 13 is bifurcated so as to form two forks 25 between which the cam is located, and in the forks 25 the spindle 26 of the lever 12 is rotatably mounted. This spindle is rigidly secured to the cam 24 by means of a set-screw 27 (see Fig. 3).

While I realize that it is common in mechanism of different kinds to employ cams to actuate any part which is to be moved, special attention is called to the features of construction of the cam 24, as illustrated in Fig. 3. The portion 28 of the operating face of the cam which corresponds to the angle α is abrupt or steep as compared with the remainder of the operating face of the cam, and, hence, a movement of the lever 12 through this small angle will result in relatively rapid movement of the valve. The portion 29 of the cam, which corresponds to the angle γ is shaped to produce very slow movement of the valve. In other words, in closing the valve, the movement of the lever 12 through the angle α will move the valve rapidly to a position where it is substantially closed, or in engagement with its seat, while a continued movement of the said lever after the valve has been brought to the position suggested will move the valve slowly and with great force into tight contact with its seat and insure that it will not leak when closed.

The valve disk 7 may be provided with a boss 30 where it is secured to the stem 40 and where such a boss is used I provide a recess or a counter-sunk bore 31 in the bonnet to provide clearance for the boss and permit the very complete opening of the valve such as that indicated in Figure 1.

45 The bore 22 between the forks 25 of the bracket 13 becomes transformed into two oppositely disposed grooves or guide ways 32 which receive the opposite sides of the round member or ball 23.

50 The lower side of the valve may be formed into a threaded nipple 33 to which a hose may be attached if desired where it is not convenient to drain the tub directly into a bucket.

55 It will be noted that the spring 19 performs a double function: It operates to open the valve and it also operates to exert thrust upon the rigid washer 21 which holds the packing against the packing seat which is formed by the bottom of the bore 14.

It is understood that the embodiment of the invention described herein is only one of the many embodiments my invention may

take, and I do not wish to be limited in the practice of my invention, nor in my claims 65 to the particular embodiment set forth.

What I claim is:

1. A quick-opening valve comprising the combination of a valve-body having a valve-seat with an opening therethrough, a bonnet detachably secured to the body, a stem guided to slide through the bonnet having a head at its outer end, a disk carried at the inner end of the stem adapted to come upon the seat to close the valve, a bracket secured to 75 and projecting outwardly from the bonnet and having a bore receiving and guiding said head, said bracket having a pair of forks, a lever rotatably mounted in said forks, a cam rigidly secured to said lever and mounted 80 between said forks, a round body guided in said bore and received between the cam and the head to impart movement from the cam to the stem to force the valve disk upon the seat, and a coil-spring around the stem 85 for moving the stem to open the valve.

2. A quick-opening valve comprising the combination of a valve-body having a valve-seat with an opening therethrough, a bonnet detachably secured to the body, a valve-stem mounted to slide through the bonnet and having a head at its outer end, a disk carried by the inner end of the stem and adapted to come upon the seat, a bracket secured in and projecting outwardly from 90 said bonnet and having a bore receiving and guiding said head, a packing disposed around the stem, a spring located in said bore disposed around the stem, thrusting against the head and exerting its pressure against the 100 packing, a cam carried in said bracket and having a lever for operating the same, and a round body guided in the bore of said bracket between the head and the cam.

3. A quick-opening and closing valve comprising the combination of a casing having a valve-seat with an opening therethrough, a valve mounted within the casing and guided to move toward and from the seat, a lever supported on the casing, a cam actuated thereby and co-operating with the valve to move the same toward its seat, a spring for moving the valve away from its seat, said cam having a portion of rapidly increasing height adapted to move the valve 110 quickly onto its seat by movement of the lever through an angle representing less than one-half of the throw of the lever, and a portion increasing in height less rapidly immediately following the first named cam 115 portion and adapted to move the valve gradually when it lies upon its seat.

In testimony whereof, I have hereunto set my hand.

JOSEPH MESSMER,
